COMBINATION AIR DEFLECTOR AND DIVERTER FOR AUTOMOBILES

Klaus Frederick Nowak, %Advanced Car Specialties Ltd.,
670 Bayview Ave., Toronto, Ontario, Canada

Filed Sept. 25, 1961, Ser. No. 66,833

Term of patent 7 years

(Cl. D14—6)

FIGURE 1 is a front elevational view of a combination air deflector and diverter for automobiles, showing my new design;

FIGURE 2 is a side elevational view taken from the left of FIGURE 1;

FIGURE 3 is a top plan view of FIGURE 1; and

FIGURE 4 is a rear elevational view of a combination air deflector and diverter for automobiles as shown in FIGURE 1.

I claim:

The ornamental design for a combination air deflector and diverter for automobiles, as shown.
